DOOR CHECK

Earl H. Croskey and Victor M. Hackman, Cedar
Rapids, Iowa, assignors of one-third to Clayton
W. Mossman, Cedar Rapids, Iowa

Application December 8, 1945, Serial No. 633,710

6 Claims. (Cl. 16—49)

1

The present invention relates generally to door checks and like devices.

The object and general nature of this invention is the provision of a simple and inexpensive door check in which means is provided for automatically holding the door open when it is opened and for automatically holding the door closed after it is closed.

A further main object of this invention is the provision of an improved door check particularly well adapted for use on the doors of panel trucks and the like. Further, it is a feature of this invention to provide a door check of this type in which an over-center spring-biased linkage holds the door either closed or open, as desired. It is an additional feature of this invention to provide means for cushioning the opening movement of the door.

These and other objects and advantages of this invention will be apparent from the following detailed description of one specific embodiment, which is illustrated in the accompanying drawings.

In the drawings:

Figure 1 is a perspective view representative of the rear end of a delivery truck in which the present invention has been incorporated, the invention, however, being shown in exaggerated size relative to the truck body.

Figure 2 is an enlarged fragmentary view of the door check mechanism as it would appear when the door is in the open position, and Figure 3 is a similar view showing the mechanism with the door in the closed position.

The delivery truck or the like, in which the present invention is incorporated, is indicated by the reference number 1 and has a rear door frame 2 in which a rear door 3 is mounted by means such as the upper and lower hinges 4, which establish a generally vertical hinge axis which may incline forwardly to a certain degree, depending upon the particular style and/or construction of the truck body.

The door check structure, with which the present invention is more particularly concerned, is indicated in its entirety by the reference numeral 7 and comprises a support in the form of a guide rod 8, the ends of which are received in two angle brackets 9 and 10 by which the rod is fixed to the upper part of the door frame 2, thus being out of the way when loading and unloading the truck. The guide rod 8 may be secured to the angle brackets by means such as the nuts 21.

A bracket 12 is affixed to the door 3 adjacent the hinge axis, but spaced a slight distance there-

2

from as indicated in the drawings, and is apertured to receive a pin 11 or the like by which a link 13 is pivotally connected thereto. The other end of the link 13 is also pivotally connected and in a similar manner, as at 14, to a lug 15 that forms a part of a slide 16, this slide being mounted on the rod or support 8 and slideable thereon. A spring 18 is disposed on the rod 8 between the bracket 9 and the slide 16, and an auxiliary spring 19 is disposed at the other side of the slide, between the latter and the other bracket 10. The door bracket 12 is so disposed, as best shown in Figure 3, that when the door 3 is closed, the pin 11 lies inwardly of a dead-center line joining the hinge axis of the door and the link pivot 14, so that the spring 18, which is compressed when the door is closed, acts to hold the door closed with a firm and positive spring action. However, when the door is opened, the pin 11 passes across said dead-center line and, as best shown in Figure 2, lies outwardly of the line joining the pivot 14 and the hinge axis of the door, whereby the force of the spring 18 biases the door outwardly and serves to hold it open. In this position, the auxiliary buffer spring 19 opposes the spring 18, serving to cushion the outward movement of the door when it is being opened.

It is, of course, understood that a door check mechanism embodying the principles of our invention may be applied to doors other than those of trucks.

Although we have described a specific embodiment of our invention, it is apparent that modifications thereof may be made by those skilled in the art. Such modifications may be made without departing from the spirit and scope of our invention as set forth in the appended claims.

What we claim and desire to secure by Letters Patent is:

1. A door check for a door hinged to means serving as a frame, comprising a pair of brackets fixed to said door frame means, a rod carried thereby, a slide mounted on said rod and having an apertured lug, a spring carried by said rod and disposed between the said slide and the one of said brackets most remote from the door hinges, a second apertured lug, a link connecting said lugs, and means fixing said second lug to said door in a position relative to the hinge axis thereof such that, in the closed position of the door, said second lug moves into an overcenter position whereby said spring acts through said slide and link to yieldably hold said door in a closed position.
2. A door check for a door hinged to means

serving as a door frame, comprising a support fixed to said frame, a slide shiftable on said support, a spring acting against said slide to urge the slide in one direction, an apertured section on said slide, a link pivoted to said apertured section at one end, means pivoting said link to the door at the other end, said means comprising a part fixed to the door in such a position relative to the hinge axis of the door that when the door is closed said part moves into a position inwardly of a dead-center line connecting the hinge axis and said apertured section, whereby the force of said spring acts to hold the door closed.

3. The invention as defined in claim 2, further characterized by said link pivoting means being located on the door so that when the door is open said part is disposed outwardly of said line, whereby the force of said spring serves to hold the door open.

4. The invention as defined in claim 2, further characterized by said link pivoting means being located on the door so that when the door is open said part is disposed outwardly of said line, whereby the force of said spring serves to hold the door open, and a second spring on said support on the other side of said slide and acting to cushion the opening action of the door after said part has been moved outwardly of said dead-center line.

5. A door check for a door hinged to means serving as a door frame, comprising a rod disposed horizontally at the upper part of said door frame generally parallel to the plane of the door opening, means fixing said support to said frame, a slide thereon, a spring acting against said slide to move the latter in one direction along said rod, a bracket fixed to the door adjacent the hinge axis, and a link extending between said

slide and said bracket, the latter being located in a position such that when the door is closed said bracket is disposed to the inside of a dead-center line extending from the hinge axis to said slide.

6. A door check for a delivery truck having a rear door swingable about a generally vertical axis, comprising a support adapted to be disposed in the upper part of the truck body so as to not interfere with access to the truck, a slide on said support and shiftable thereon, a bracket adapted to be fixed to said door adjacent the hinge axis thereof, a link pivoted at one end to said slide and at the other end to said bracket, a spring acting between one end of said support and said slide, said bracket being so disposed that, when the door is closed, said bracket lies inwardly of a dead-center line connecting the hinge axis and said slide, whereby the said spring acts against the slide to hold said door closed, and a cushioning spring disposed between said slide and the other end of said support, said spring serving to resiliently resist opening of the door beyond a predetermined point, the said bracket being disposed outwardly of said dead-center line when the door is opened whereby the first mentioned spring serves to hold said door open.
